CLAIM

The ornamental design for an oven, as shown and described.

DESCRIPTION

FIG. 1 is a front perspective view of an oven showing my new design;

FIG. 2 is a front view thereof; and,

FIG. 3 is a right side view thereof.

The broken lines representing the handle and the elongated ovular region form no part of the claimed design. The broken lines depicting the remainder of the oven form no part of the claimed design.

1 Claim, 3 Drawing Sheets
